UNITED STATES PATENT OFFICE.

JOHN H. BELL, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,296,740.

Specification of Letters Patent. Patented Mar. 11, 1919.

Application filed April 22, 1918. Serial No. 230,193.

To all whom it may concern:

Be it known that I, JOHN H. BELL, a citizen of the United States, residing at South Orange, in the county of Essex, State 5 of New Jersey, have invented certain new and useful Improvements in Telegraph Systems, of which the following is a full, clear, concise, and exact description.

This invention relates to telegraph systems and more particularly to telegraph transmitter systems.

The principal object of this invention is to provide a system for improving the definition of telegraphic impulses in connection 15 with line conductors having high electrostatic capacity as commonly encountered in connection with submarine cable working.

To the above end, the phenomenon known 20 as a wandering zero effect is counteracted by means of a plurality of electroresponsive devices arranged in such a manner that signaling current will be effective with a line conductor only at the beginning and end of 25 an impulse interval. This arrangement further provides that the line conductor will be connected to the earth during periods intermediate the beginning and ending of an impulse and also during intervals corresponding 30 with spacing periods between impulses.

This invention is illustrated diagrammatically in the accompanying drawing in which for the sake of clearness, only so much of 35 a telegraph system has been shown as will be necessary to a clear understanding of the features of this invention.

In the drawing, Figure 1, is shown a transmitting equipment suitable for transmission 40 of telegraphic signals in accordance with the features of this invention; in Fig. 2 is shown a theoretical form of impulse intervals which correspond in the matter of time with a circuit controlling device, the operations of which initiate the 45 sending of impulses. In Fig. 3 is shown, in theoretical form, the electrical effects established by signaling impulses in a line conductor. An alternate arrangement shown 50 in Fig. 4 may be substituted for the arrangement shown in Fig. 1.

In describing the operation of this system, reference character L indicates a line conductor which is connected to a moving contact member of relay 1. A source of posi-

tively poled and grounded current 2 is connected through a winding 3 of this relay, thence by way of normal contacts 5, of a transmitting key 4, to complete circuit through a polarized relay 6, and a condenser 7 to earth. Relay 1 may be of a neutral type, the armature of which is normally retracted to establish its contacts 8 as shown in the drawing, thereby completing a circuit from the line L to earth. The polar relay 6 may be of a non-biased type, that is, its armature will remain in the position to which it may have been moved by an impulse of current until an impulse of current in the opposite direction, through the winding 13 of the relay, biases the armature to the other side. In the positions in which the circuits are shown in the drawing, it will be clear that circuit for an impulse of positive current is completed through the relay 1, 75 key 5, and relay 6, as already traced, will have established a positive bias of the relay 6, whereby its contacts 9 will continue closed until the key 4 may be operated. If now the key 4 is depressed its contacts 5 will 80 be separated, while its contacts 11 will be closed. A circuit may now be traced from a negatively poled and grounded battery 12, through a winding 13 of the relay 1, contacts 11 of the key 4, thence through the 85 winding of the relay 6 and the condenser 7 to earth. This impulse of negative current will bias the armature of the polar relay 6 to close its contacts 14, thereby completing a circuit from a negatively poled line or 90 cable battery 15 to the contacts of the relay 1. The impulse of current just traced through the winding 13 will cause the relay 1 to momentarily attract its armature, thereby separating its contacts 8 to disconnect 95 the line L from earth and to connect it over the contacts 16 of this relay with the battery 15. The period during which the contacts 16 of the relay 1 may remain closed is relatively short and corresponds with the time 100 constants of the circuit with respect to the capacity effect in the condenser 7 and the operating moment of the relay 1. Releasing of the key 4 disconnects the circuit from negative battery 12, and completes the circuit already traced from the positively poled battery 2. This circuit change causes the armature of the relay 6 to be oppositely biased to connect the positively poled cable battery 10 over the relay contacts 9 and the 110

contacts 16 of relay 1 with the line conductor, it being understood that the momentary effect of current through winding 3 of the relay 1 resulted in a momentary operation of this relay.

- From the foregoing description it will be clear that operation of the key 4 in a manner suitable for transmitting telegraphic signals results in establishing either the line 10 battery 10 or the line battery 15 momentarily with the line conductor L, once at the beginning of an impulse interval and once at the termination of an impulse interval, this order of current effects being present with the line, 15 irrespective of the character of the signaling impulses, that is, the current is the same whether a short interval or a long interval impulse, as dots and dashes respectively, may be transmitted.
- 20 Referring to Fig. 2 of the drawing, the straight dotted line indicated by the zero character represents the true potential or zero current line of the cable, while the shaded irregular line indicates the time intervals which correspond with the operation of the transmitting key 4. The sections of the shaded line which are on the upper or positive side of the zero line may be considered as representing the time intervals 25 during which the key 4 may be in its normal position in which the positively poled battery 2 stands connected as shown in the drawing, while the sections of the shaded line which are below or on the negative side of the zero line correspond with the time intervals 30 during which the key 4 may be held depressed in establishing the negatively poled battery 12 over the circuit already traced.
- 35 40 In Fig. 3, the shaded irregular line corresponds with time intervals during which signaling currents may be included with the line 1 corresponding with key manipulation intervals illustrated in Fig. 2, while the zero intervals indicated by the reference character E will be understood to correspond with periods during which the line conductor L is connected to earth. For the key manipulations illustrated in Fig. 2, reference to Fig. 3 will clearly indicate that 45 on the instant the circuit was completed from the positively poled battery 2, the momentary operation of the relay 1, in phase with the biasing of the relay 6, permitted a relatively short interval of positively poled current to reach the line L, and at the instant the key 4 was depressed to complete a circuit from the negative battery 12, relay 1 50 was momentarily operated in phase with the corresponding biasing of the relay 6 to momentarily render an impulse of negative current effective with the line. Since the relay 1 may only attract its armature during the relatively short periods during which reversals and current discharging or charging 55

effects are active in the condenser 7, it will be clear that at all times during which the condenser 7 may be fully charged with the polarity of either of the batteries 2 and 12, no effect will be present in the relay 1. The 70 armature of this relay will, therefore, stand in its normal position, during such times, to ground the line L. Such grounding intervals therefore correspond with the intervals indicated by the character E in Fig. 3 of 75 the drawing.

Referring to Fig. 4, this alternate arrangement differs from the arrangement shown in Fig. 1 in that a single wound neutral relay is substituted for the compound wound relay. As shown the single wound relay is connected in series with the lead which extends from the key 4 to the polar relay 6. Similar characters of reference have been employed in designating like or corresponding parts in the Figs. 1 and 4 and as the same service results are obtainable with the plan shown in the last figure, the description already given in connection with the first plan will render further description of 80 the system unnecessary.

From the foregoing description it will be clear that true reversals of current polarities only become effective with a line conductor irrespective of the duration of the 85 impulses. In this manner an asymmetrical charging of the cable is prevented and a relative true zero current condition maintained therein. As well understood in the art such desirable condition of the cable results not only in improving the definition of the impulses as received at a distant station on a cable, but also results in a decided gain 90 with respect to the speed at which signaling impulses may be transmitted and properly received.

Although a manually operated key has, for convenience of description, been shown in the present invention, it will be understood that this elementary arrangement 100 will clearly indicate that any suitable type of automatic transmitter, such as a tape controlled transmitter, may be employed and that the transmission code may be based on intervals of positive and negative impulses, each of equal duration as present in the well-known five-unit impulse code of 105 Baudot.

The arrangement shown and described in this invention is considered to represent a 110 preferred embodiment of the system. It will be obvious, however, that various changes in the organization of an equipment for arriving at the service results described, may be made without departing 115 from the spirit of this invention.

What is claimed is:

1. In a telegraph transmitting system, a local circuit comprising a neutral relay, a transmitting key, a polar relay and a con- 130

denser, line terminal circuits including a plurality of oppositely poled current sources and contacts of said polar relay, and contacts controlled by said neutral relay for connecting said line circuit to earth during periods that no change of current effects are taking place in said condenser.

2. In a telegraph transmitting system, a line circuit, a neutral relay, a polar relay and a condenser, sources of current, transmitting means for selectively connecting different current polarities through a circuit formed by said relays and condenser, means controlled by said polar relay for selecting different current polarities to be controlled by said neutral relay, and means controlled by said neutral relay for rendering said selected polarities effective with the line circuit during moments current effects 20 are active in said condenser.

3. In a telegraph transmitting system, a line circuit, a plurality of current sources, a compound wound relay, a polar relay, a transmitting key for alternately connecting 25 different windings of said compound wound relay in series with said sources of current and said polar relay, a condenser included in said circuit, and means jointly controlled by said relays for momentarily connecting 30 said sources of current with said line conductor to effect signaling.

4. In a telegraph system, a line circuit, sources of current, a compound wound relay, a polar relay, a condenser, a transmitting means for selectively connecting said 35 sources of current through different windings of said compound wound relay, said polar relay and said condenser, means controlled by said polar relay for selecting different polarities from said sources of current, and means controlled by said compound wound relay for connecting said line circuit either to earth or to the current polarities selected by said polar relay.

5. In a telegraph transmitting system, a 40 line circuit, a local circuit comprising a compound wound relay, a transmitting key, a polar relay, a condenser and sources of oppositely poled currents, a terminal circuit for said line comprising an earth connection, 50 pluralities of oppositely poled current sources and contacts of said polar relay, and means controlled by said compound wound relay for alternately connecting said line circuit over said earth connection or the terminal circuit controlled by said polar relay 55 in a manner corresponding with the operation of said transmitting key in controlling the operation of said relays.

In witness whereof, I hereunto subscribe 60 my name this 15th day of April, A. D. 1918.

JOHN H. BELL.
